(57) **CLAIM**

The ornamental design for a combined baby wrap and comforter, as shown and described.

DESCRIPTION

FIG. 1 is a top perspective view of the combined baby wrap and comforter shown in an open position;

FIG. 2 is a top plan view of the combined baby wrap and comforter; with the flap unfolded in an up position;

FIG. 3 is a side plan view of the opened baby wrap;

FIG. 4 is a rear plan view of the opened baby wrap;

FIG. 5 is an end plan view of the opened baby wrap;

FIG. 6 is an opposite end plan view of the opened baby wrap;

FIG. 7 is an end plan view of the opened baby wrap;

FIG. 8 is a rear view of the baby wrap and combined comforter; shown in an alternate folded position of use; and, FIG. 9 is a front plan view of the folded baby wrap.

In the drawings, the broken lines represent environmental structure forming no part of the claim.
